BALL VALVE OR THE LIKE

John P. Magos, Wilmette, Ill., assignor to Crane Co.,
Chicago, Ill., a corporation of Illinois

Filed Aug. 8, 1962, Ser. No. 71,217

Term of patent 14 years

(Cl. D78—1)

Des. 198,294

Fig. 3.

FIG. 1 is a perspective view of the front and one side of a ball valve or the like embodying my new design; FIG. 2 is a side view thereof; and FIG. 3 is a bottom view thereof.

The rear and side not shown are the same as, respectively, the front shown in FIG. 1 and the side shown in FIG. 2.

I claim:

The ornamental design for a ball valve or the like, substantially as shown and described.
